UNITED STATES PATENT OFFICE

GEORGE KOVASIC, OF CAMBRIA, WYOMING.

WORK-BOX.

No. 894,960.

Specification of Letters Patent.

Patented Aug. 4, 1908.

Application filed April 22, 1908. Serial No. 428,553.

To all whom it may concern:

Be it known that I, GEORGE KOVASIC, a citizen of the United States, and a resident of Cambria, in the county of Weston and State of Wyoming, have invented certain new and useful Improvements in Work-Boxes, of which the following is a specification.

The invention relates to improvements in work-boxes of that description which are used by women to hold the implements and other appurtenances used in sewing.

It has for its object the provision of a device that will hold such articles so as to be ready and convenient for use.

It consists in the novel construction, combination and arrangement of parts, such as will be hereinafter fully described, pointed out in the appended claims and illustrated in the accompanying drawings.

In the drawings, in which similar reference characters designate corresponding parts, Figure 1 is a perspective view of a work-box embodying the invention, the lid being open. Fig. 2 is a detail perspective view showing one of the transverse partitions. Fig. 3 is a longitudinal sectional view, showing one of the transverse partitions in a raised position.

The closure is of a rectangular box-formation and comprises the body part 4 and the lid 5 hinged thereto. In one end of the body part is the fixed transverse partition 6 forming between the same and the end-wall 7 the compartment 8. Extending between the transverse partition 6 and the opposite end-wall 9 are the longitudinal partitions 10. At intervals in the longitudinal partitions are the angular slots 11 having at their inner ends the bearings 12. Mounted in these bearings are the rods 13 for carrying the spools of thread. The rods can be easily placed in their bearings by passing them through the angular slots. The latter, by reason of their angular shape, prevent an accidental displacement of the rods.

At the end of the main body of the work-box in which is fixed the transverse partition 6 is the removable transverse partition 14 extending across the ends of the longitudinal partitions 10, thereby forming the compartments 15. In the latter are the removable drawers 17. The partition 14 is provided with slots 18 to register with the vertical parts of the angular slots 11 in the adjacent ends of the longitudinal partitions 10. When in place the partition 14 holds in place the rod mounted in the angular slots with which the partition registers. By displacing the partition the rod can be readily removed. While only one removable partition is shown, yet it is obvious that others may be provided for the other rods. A supplemental lid 19, hinged to the body part, is provided for the compartments 6 and 15. The inside of the lid 5 may be provided with a mirror or other ornamentation.

Having thus described my invention, what I claim and desire to secure by Letters-Patent is,

1. In a work-box, the body part, partitions in said body part having angular slots, spool-holding rods removably mounted in said slots, and a removable partition registering with said slots.

2. In a work-box, the body part, transverse partitions in one end of said body part forming compartments, a supplemental lid for said compartments, longitudinal partitions extending from said transverse partitions to the other end of said body part having angular slots, and spool-holding rods mounted in said slots.

In testimony whereof I hereunto affix my signature in the presence of two witnesses.

GEORGE KOVASIC.
